PLASTIC SHEET MATERIAL

Russel Wright, New York, N. Y.

Application December 12, 1955, Serial No. 39,299

Term of patent 14 years

(Cl. D87—3)

The figure is a plan view of a plastic sheet material showing my new design, a unit being enclosed by the broken lines on the drawing.

I claim:

The ornamental design for a plastic sheet material, substantially as shown.
